HANDLING IMPLEMENT FOR PLATE GLASS AND THE LIKE

Filed July 9, 1936

FIG. 1.

FIG. 2.

UNITED STATES PATENT OFFICE

2,127,154

HANDLING IMPLEMENT FOR PLATE GLASS
AND THE LIKEGeorge W. Burk, Chicago, Ill., assignor to Adolph
F. Lange, doing business as Henry G. Lange Ma-
chine Works, Chicago, Ill.

Application July 9, 1936, Serial No. 89,815

4 Claims. (Cl. 294—64)

This invention relates to implements for use in handling plate glass and the like.

In manipulating plate glass and analogous frangible sheets, which are frequently of large size and considerable weight, great difficulty is experienced in lifting the sheet from a table or the bed of a processing machine and in transporting the sheet. The services of two operators are commonly required for sheets of relatively large size, and difficulty is experienced by the operators in grasping the sheets and securing and maintaining a firm hold thereon.

A principal object of the present invention is to provide a tool or implement which can be readily secured to a single surface of such sheet and which will adhere tenaciously thereto and be capable of instant release therefrom when desired, and which will provide a convenient grip by which a single operator only may easily and surely lift the sheet and transport it.

The device embodying the invention includes suction disc elements mounted in a member having a grip portion, and includes means for creating a reduced air pressure between the suction disc elements and the sheet to which they are applied. I am aware that it has heretofore been proposed to secure various articles and devices to plane surfaces by means including suction discs, and accordingly I do not claim this concept broadly to be original with me. The novelty of the present invention resides in the provision of a pair or more of suction disc elements carried by a member having a grip portion, and in certain other useful and convenient features contributing to the attainment of the objects hereinabove specified.

Ancillary objects of the invention are the provision of a handling implement of the type indicated which will be simple and inexpensive to manufacture and durable and foolproof in use.

The principles of the invention may be embodied in a device as illustrated in the accompanying drawing and described hereinafter. It is to be understood that the invention is capable of embodiment in other forms than that shown, which latter is selected as a preferred embodiment and is given by way of exemplification and not limitation.

In the accompanying drawing:

50 Figure 1 is a top plan view of an embodiment of the invention; and

Figure 2 is a central longitudinal sectional view showing the device associated with a sheet of glass and in process of being secured thereto.

55 The device comprises a member which may

conveniently be made hollow to save weight and expense and may be cast from aluminum or other metal, although the material and the manner of fabricating form no part of the invention. The member includes an intermediate grip portion 1, of a shape and size adapted to be grasped by the hand of an operator. The intermediate portion is therefore conveniently made tubular, and integrally or otherwise provided at each of its ends is an enlargement 2, which is preferably cup-shaped, having a circular lip 3 and a generally hollow interior. The lips 3 of the two enlargements are disposed in a single plane, which is spaced sufficiently from the lower surface of the intermediate portion 1 to provide room for the fingers of the operator when grasped about the grip portion.

In each enlargement 2 there is provided a suction disc element 4, conveniently made of rubber having a smooth bottom face and being shaped to conform to the contour of the lip 3. I find it convenient to provide inwardly of the lip of each enlargement an annular shoulder 5 which constitutes an abutment for the margin of the suction disc against which the disc seats. Preferably the thickness of the disc at its outer margins is greater than the distance between the shoulder 5 and the lip 3, so that the disc projects somewhat from the enlargement and the metal of the enlargement is protected from contact with any sheet to which the implement may be applied.

Embedded in each disc 4 is one end of a stem 6. A convenient manner of effecting a durable union between the stem and the disc is to flare the bottom of the stem or to securely attach thereto a relatively thin plate 7 of metal or the like around which the disc is molded, so that the stem is securely maintained bonded to the disc. The opposite end of the stem projects through an opening in the rear face of the enlargement 2. A helical spring 8 is disposed under compression around the stem 6 between the opposite inner faces of the enlargement 2 and the disc 4, so that the spring urges the disc outwardly.

I provide means for imparting lengthwise movement to the stem to pull the disc against the tension of spring 8 and into the enlargement 2. It will be evident that when the disc is so moved, after being engaged with the surface of an object like the sheet of plate glass designated 9, a powerful partial vacuum will be created between the disc and the sheet, causing the disc to adhere tenaciously to the sheet. I find it convenient to provide means for imparting lengthwise movement to the stem 6 by pivoting to the projecting

end of the stem a lever 10 having a pair of cam faces 11 and 12. These cam faces bear alternatively against a small wear plate 13 in the form of a washer surrounding the stem on the outer face of the enlargement 2. The lever 10 is thus fulcrumed on the wear plate, which is effectively the rear face of the enlargement 2, and the cam surfaces 11 and 12 cause the lever to assume, when rocked about its pivot 14, either one of two positions. In one position, shown in the lower part of Fig. 2, cam face 11 is engaged with the enlargement or the wear plate and the stem is in its forwardly projecting position, disposing the disc in substantially plane condition. In the other position of the lever 10, shown at the upper portion of Fig. 2, cam face 12 is engaged with the enlargement or wear plate and the stem is in its retracted position, producing a concavity in the disc 4 and a high degree of vacuum between it and the sheet 9.

In use the implement is applied to a sheet such as that shown at 9, with the levers upstanding from the enlargements as shown in the lower portion of Fig. 2. The levers are then depressed, retracting the stem and the central area of the disc 4 and creating the partial vacuum between the discs and the sheet 9, as shown in the upper portion of Fig. 2. Grip portion 1 of the tool is then grasped by the operator, the tool thus providing a handle firmly attached to the sheet so that the sheet may be moved about and operated upon as may be desired. When it is desired to release the sheet from the implement it is only necessary to lift the levers 10. Atmospheric pressure and spring 8 thereupon restore the discs to their plane condition, destroying the vacuum beneath each disc and releasing the sheet.

An important feature of the invention consists in proportioning the parts at each opposite end similarly so that when the levers are depressed to one of their two possible positions the degree of vacuum produced under each disc is substantially identical. In practice the parts are proportioned to make this vacuum ample to secure the tool firmly against any tension force which it may be called upon to withstand.

Another important feature of the invention resides in the construction whereby nothing but rubber, or the composition of which the discs 4 are made, can touch the sheet 9 during use of the implement. This feature is attained by arranging the discs 4 to project somewhat from the enlargements 2, and by embedding each stem 6 and plate 7 in the disc instead of piercing the disc by the stem and disposing the plate 7 on the bottom, operating face of the disc.

A further important feature of the invention consists in making the stem 6 of square or other polygonal cross-section, and similarly shaping the opening in the enlargements 2 through which the stem projects. The stems are thus prevented from rotating and the levers 10 are consequently always disposed to rock in substantially the plane of the axis of the grip portion 1. This constraint of the levers 10 facilitates the operation of depressing and lifting them, so that these operations can be accomplished always by the same diverging or converging movements of the palms of the operator's hands.

Other features and advantages of the device will, it is thought, be evident to those skilled in the art, and all such features, whether embodied

in the device as illustrated or any equivalent constructions within the scope of the appended claims, are to be deemed, within the purview thereof.

I claim:

1. A handling implement for plate glass and the like comprising a member having an intermediate grip portion adapted to be grasped by the hand and having cup-shaped enlargements at its opposite ends, a suction disc element supported in each enlargement, spring means compressed between the central area of each suction disc element and the opposite inner surface of the enlargement for normally maintaining said element in flat condition, means for retracting the central area of each suction disc element comprising a stem having one end embedded in the element and its opposite end projecting from the enlargement, and manually operable means connected to said projecting end for imparting lengthwise movement to said stem.

2. A handling implement for plate glass and the like comprising a member having an intermediate grip portion adapted to be grasped by the hand and having at each opposite end a cup-shaped enlargement having a polygonal opening through its rear wall, a suction disc element in each enlargement, a stem having one end secured to the disc and its other end having a cross-sectional shape corresponding to that of the opening and extending non-rotatably through said opening, a lever pivoted to the extended end of the stem for swinging movement in a single plane to reciprocate the stem and retract and release the disc, and spring means compressed between the retractile portion of each disc and the opposite inner wall of the adjacent enlargement for normally maintaining the disc in flat condition.

3. A handling implement for plate glass and the like comprising a member having a grip portion adapted to be grasped by the hand and having a cup-shaped enlargement carried by the grip portion, a suction disc element supported in the enlargement, spring means compressed between the central area of the suction disc element and the opposite inner surface of the enlargement for normally maintaining said element in flat condition, means for retracting the central area of the suction disc element comprising a stem having one end embedded in the element and its opposite end projecting from the enlargement, and manually operable means connected to said projecting end for imparting lengthwise movement to said stem.

4. A handling implement for plate glass and the like comprising a member having a grip portion adapted to be grasped by the hand and having a cup-shaped enlargement carried by the grip portion having a polygonal opening through its rear wall, a suction disc element in the enlargement, a stem having one end secured to the disc and its other end having a cross-sectional shape corresponding to that of the opening and extending non-rotatably through said opening, a lever pivoted to the extended end of the stem for swinging movement in a single plane to reciprocate the stem and retract and release the disc, and spring means compressed between the retractile portion of the disc and the opposite inner wall of the enlargement for normally maintaining the disc in flat condition.

GEORGE W. BURK.
